UNITED STATES PATENT OFFICE

105,855

DESIGN FOR A DRESS ENSEMBLE

Rose Feintuck, New York, N. Y.

Application June 28, 1937, Serial No. 70,091

Term of patent 3½ years

To all whom it may concern:

Be it known that I, Rose Feintuck, a citizen of the United States of America, residing in Manhattan, county of New York, and State of New York, have invented a new, original, and ornamental Design for a Dress Ensemble, of which the following is a specification, reference being had to the accompanying drawing, forming part thereof, wherein,

Figure 1 is a front view of a dress ensemble showing my new design.

Figure 2 is a front view of the dress unit of the dress ensemble shown in Figure 1.

Figure 3 is a rear view of the dress unit of the dress ensemble.

Figure 4 is a rear view of the jacket unit of the dress ensemble shown in Figure 1.

The characteristic feature of my design resides in the combination on the one piece dress section of my ensemble of the tucks arranged below the waistline as shown, said tucks presenting a girdle-like appearance.

I claim:

The ornamental design for a dress ensemble, substantially as shown, and described.

ROSE FEINTUCK.
